UNITED STATES PATENT OFFICE.

ANGELO PAPOULIAS, OF STEUBENVILLE, OHIO.

CHANGE-MAKING DEVICE.

Application filed January 17, 1922. Serial No. 529,891.

To all whom it may concern:

Be it known that I, ANGELO PAPOULIAS, a citizen of the United States, residing at Steubenville, in the county of Jefferson and State 5 of Ohio, have invented certain new and useful Improvement in Change-Making Devices, of which the following is a specification.

This invention relates to change making 10 devices for automatically delivering the correct change, thereby preventing error in the amount of cash refunded where the difference between the purchase price, admission or the like, is less than the amount tendered.

15 A primary object of the invention is to provide a simple and practical machine of the character set forth which requires little or no calculation on the part of the operator to obtain the desired change, thereby making 20 the invention especially useful to persons not thoroughly familiar with the value of coins to be given in change or, on the other hand, greatly assisting and insuring accuracy in change-making operations of any kind.

25 That is to say, it is proposed to provide a machine having keys representing the amount of the purchase, and keys representing the amount tendered, so that it is only necessary for the operator to manipulate the 30 amount purchased key and then the amount tendered key to receive the desired change.

A further object of the invention is to provide a release key which will automatically 35 release all of the amount purchased keys in case of error without in any way affecting the other instrumentalities of the device, thereby enabling the operator to depress the correct keys for the desired change-making operation.

40 With the above and other objects in view which will more readily appear as the nature of the invention is better understood, the same consists in the novel features of construction, combination and arrangement 45 of parts hereinafter more fully described, illustrated and claimed.

A preferred and practical embodiment of the invention is shown in the accompanying drawings, in which—

50 Figure 1 is a plan view of the top of the device;

Figure 2 is a front elevation;

Figure 3 is a vertical sectional view taken on the line 3—3 of Figure 1;

55 Figure 4 is a horizontal sectional view taken on the line 4—4 of Figure 3.

Similar reference characters designate corresponding parts throughout the several figures of the drawings.

While it will of course be understood that the change making mechanism constituting the present invention may be housed or concealed by any special design or type of cover or casing, a practical embodiment is shown in the accompanying drawings from which it will be observed that the casing 1 has the top 2 through which the stems of the various keys project, as will hereinafter more fully appear while the front side thereof may be provided with a coin magazine, designated generally 70 as M, and having a transparent window 3 and a hinged cover 4 for rendering the coin holders 5 accessible for filling.

At the lower end of the coin holders 5 suitable means 6 is provided for supporting the stack of coins α arranged within the holder, while beneath the said holders a suitable delivery chute 7 may be provided for the purpose of conveying the coins to be given in change to the delivery outlet 8.

80 As the novel features of the present improvement are susceptible of embodiment in units for changing coins of various denominations, it will be apparent that a description of one unit will apply to the others since the structural features may be duplicated to any desired degree according to the number of coins available to make the desired change values from the amount tendered.

Accordingly, by way of example the unit 90 representing the twenty-five cent coin value may be conveniently utilized to illustrate the features of the present improvement. This unit is illustrated in Figures 3 and 4 of the drawings from which it will be observed that 95 the same includes in its general organization a coin ejector A, a plunger bar B, and a selective ejector engaging member C adapted to be controlled by the amount purchased key D in such a way that it will be inoperative upon the manipulation of the amount tendered key E, as will hereinafter more fully appear. Also the unit includes a releasing device R which may effect the release 100 of the amount purchased key D in event that an error has been made in its selection.

105 Referring first to the coin ejector A, it will be observed that the same includes an ejector stem 8, slidably supported in a frame 9, and having the coin ejecting end 10 thereof normally held retracted by a spring 11 while the end 12 thereof is arranged in the path of

movement of the shiftable ejector engaging member or hammer 13 pivotally connected as at 14 with the bar 15 of the plunger device B. This plunger bar 15 is slidably arranged within a barrel or casing 16 and is provided with the upstanding abutment pins 17 and 18 which are guided in the slots 17^a and 18^a of the casing.

For the purpose of normally maintaining the hammer 13 in axial alinement with the plunger bar 15, it is depressed by a flat spring 19 riveted or otherwise affixed to the plunger bar. As will be seen from Figure 3 the pivot pin 14 connecting the coupling member and the bar is arranged in a horizontal plane so that the spring 19 normally maintains the coupling member in the valley of the forward cut-away end of the casing 16. The front end of the hammer 13 is pivotally engaged by the lower end of the link 20 that connects it with a control lever 21 fulcrumed upon the shaft 22 and having its end 23 adapted to be engaged by the collar 24 on the stem 25 of the amount purchased key D. For the purpose of tensioning the link 20 and also holding the bar 15 in its retracted position, a spring 26 may be connected with the intermediate portion of the link and a suitable spring support 27. This arrangement makes it possible to utilize a single spring for tensioning the parts associated with the plunger bar and the connections for controlling the ejector engaging member or hammer 13.

Referring now to the amount purchased key D, it will be seen that stem 25 of this key is slidably guided in the flange 28 of a guide bar G which may be common to all of the amount purchased keys throughout the machine and whose vertical wall 29 may be provided with guide slots 30 for insuring the proper movement of the levers 21. In order to yieldingly support the amount purchased key D the intermediate part of the stem 25 is provided with an abutment collar 31 adapted to be engaged by a spring 32 resting upon the top surface of a carrier bar 33 which may also be common to the several amount purchased keys of the device.

As shown in Figure 3 the lower end of the stem 25 is of substantially of U-shaped formation, one leg of the U constituting the holder for the spring 32, while the opposite leg 34 is preferably provided with an offset latch end 35 for engaging with the keeper hook 36 of a spring pressed detent 37 pivotally supported as at 38 and constituting a restraining device for holding the keys D depressed. In connection with the substantially U-shaped formation of the end of the stem 25 it will be observed that the opposite legs of the U-shaped portion have a relatively free sliding engagement with the openings 33^a of the bar 33 so that the key

may be readily depressed against the tension of the spring 32 but cannot turn or twist so that the latch end 35 will avoid the keeper end 36 of the detent.

The amount tendered key E is the primary actuator for the plunger bar 15. As may be observed from Figure 3 of the drawings the stem 39 of the key E is slidably guided in the top 2 of the casing and the guide 40 and carries at its intermediate portion a suitable abutment collar 41 adapted to engage with the arm 42 of a crank lever 43 which is pivotally supported on the shaft 44. The other arm 45 of the lever 43 extends downwardly and may be provided at its lower end with a roller 46 for engagement with the abutment 17 of all of the plunger bars 15 of the unit as may be seen from Figure 4. Thus, when the amount tendered key E is depressed the roller 46 will slidably engage the abutments 17 and push the bars 15 forward. If the hammer 13 connected with the bar is in line with the axis of the bar as shown in full lines in Figure 3, the coin ejector 8 will be moved forward. On the other hand, if the hammer is raised, that is held in its elevated position, as shown by the dotted lines in Figure 3 due to the depression of the amount purchased key D, the forward movement of the bar 15 will be idle so far as the coin ejector is concerned.

The releasing device R which permits of correcting the amount purchased in case of error by releasing the amount purchased key D, which has been depressed inadvertently, may be common to all of the several units of the device. As shown in Figures 1 and 4, for example, this releasing device consists of the release key R exposed at the top of the casing 1 and having its stem 47 adapted to engage with the arm 48 of a lever 49 which is pivotally supported as at 50, and has an arm 51 adapted to engage with a releasing bar 52 which is common to all of the detents 37 of the several units of the device. Thus, if the amount purchased key D is depressed so that the end 35 of the stem portion of the key becomes engaged with the key end 36 of the detent through error, and it is desired to correct the error, the releasing key R makes such correction possible upon its depression, because the arm 51 of the lever 48 will engage the common release bar 52 to thereby rock the detent 37 on its axis 38 and release the key D. That the key D will return to its normal position will be apparent because the spring 32 will expand and the spring 19 will pull the hammer 13 downwardly as well as the link 20, thus causing the elevation of the end 23 of the lever 21.

The release bar 52 being common to the detents of all of the units also serves the purpose of disconnecting the end 35 from the keeper hook 36 of the detent when the

plunger bar 15 moves forward on its operative stroke to actuate the coin ejector. That is to say, as the bar 15 is moved forward by the depression of the amount tendered key 5 E through the connections already described, the abutment pin 18 of the bar 15 will advance and engage the release bar 52 and rock the detent to thereby disconnect the arm 34 of the stem for the key D to permit it to be returned to normal position and be ready for the next operation.

In order to simplify the making of change by the operator it is proposed to have as many amount tendered keys as are necessary 15 to make all change values within the given money limit of each unit, and in the case of certain purchases to deliver the change in pieces of money of the largest denomination. To that end, it is desirable to effect a combination of the operating instrumentalities 20 associated with several keys by the depression of a single amount purchased key.

For example in the twenty-five cent unit 25 the pieces of money provided to make all change values for purchases under twenty-five cents are three five-cent pieces and one ten-cent piece. Suppose a customer makes a fifteen cent purchase and tenders a twenty-five cent piece in payment. Instead of depressing the three five-cent keys individually to give the aggregate amount of the purchase, it is only necessary to depress the fifteen-cent key which will automatically 30 carry all three of the five-cent keys and their operating connections into an inoperative position. That is to say, as may be observed from Figure 4, the fifteen cent key is not connected with any of the instrumentalities for directly actuating 35 the coin ejector, but the stem 53 thereof is provided with an offset portion 54 carrying a combination depressing bar 55 which is common to all of the levers 21 of each of the five cent units. Therefore, upon the depression of the fifteen cent key the instrumentalities 40 connected with all of the five cent units will be depressed at once, thereby elevating the coupling member 13 of each five cent unit, so that when the amount tendered key 45 E indicating the twenty-five cent purchase is depressed, the forward movement of the bars 15 of each five cent unit will be idle, but the bar 15 of the ten cent unit will move forward so that its hammer 13 will engage with 50 the end 12 of the coin ejector to thereby remove a single ten cent piece from the bottom of the stack of dimes in the ten cent holder.

Obviously, amount purchased keys of other 55 denominations, such for example as the twenty cent key, may be provided with a similar combination bar 55^a, the same engaging the lever 21 of the ten cent unit and the levers 21 of the two adjacent five cent units. This arrangement may be duplicated throughout the machine at will to effect any

desired combination of units to keep the amount of the purchase in the device and eject only the difference between the amount purchased and the amount tendered, which represents the change due the patron.

In explanation of the provision of three 5¢ unit it is pointed out that this is done to give a dime and two nickels as the change from a 25¢ piece when a 5¢ purchase is made, or, on the other hand, to give three nickels 75 in change when a 10¢ purchase is made and a 25¢ piece tendered in payment. Frequently occasion arises to have small pieces of change available, and the provision of the three 5¢ and the one 10¢ unit makes this possible.

It will also be apparent that the present device may be constructed to utilize pennies as a part of the change combination, but since as a rule pennies are not desirable in change, it is preferable to provide a separate 80 penny change maker which may be conveniently placed at one end of the machine as shown in Figures 1 and 2 of the drawings. This device may be of any desired form of 85 construction and essentially includes a penny magazine 60 and an ejector 61 operating by key 62 for discharging the pennies from the magazine into the delivery chute 63.

It is believed that the operation of the device will be apparent from the foregoing description but for the purpose of illustrating a complete cycle of operation of the several units, reference may be made to Figures 3 and 4 of the drawings which illustrate in detail the change making unit for a twenty-five cent tender. Figure 3 shows one of the five cent units and for example assume that a five cent purchase is made and a twenty-five cent piece tendered in payment. In that case, the operator will depress one of the five 90 cent keys D which will have the effect of causing stem 25 thereof to descend against the tension of the spring 32 and snap the latch end 35 of the stem beneath the keeper hook 36 of the detent 37. When the key is 95 thus depressed and held by the detent, the lever 21 having been engaged by the collar 24 of the stem is rocked to its dotted line position in Figure 3 thereby pulling the hammer 13 upwardly so that when the 100 plunger bar 15 is thrown forward by the depression of the amount tendered key E, the end of the coupling member 13 will avoid the end 12 of the coin ejector. However, it 105 will be understood that the hammers 13 of the units associated with the other two five cent pieces and the ten cent piece will remain 110 in alinement with the bar 15 and move the coin ejectors of the coin values referred to, thereby ejecting two nickels and a dime as 115 the change due the patron from the transaction.

In the event that the wrong amount purchased key has been depressed it may be readily released by manipulation of the release key R, as previously described.

Without further description it is thought that the novel features of the invention will be readily apparent to those skilled in the art and it will of course be understood that 5 changes in the form, proportion and minor details of construction may be resorted to without departing from the spirit of the invention or scope of the appended claims.

I claim:

10 1. In a change making device, a money changing unit including a coin holder, a sliding plunger, an ejector separate from the plunger, and said plunger having a shiftable striking end portion arranged to normally 75 strike the ejector, a key for actuating said sliding plunger, and selective key controlled means for deflecting the said shiftable end portion of the plunger to avoid the ejector.

15 2. In a change making device, a money changing unit including a coin holder, an ejector for the holder, a sliding plunger adapted to normally engage with said ejector key operated means for actuating said sliding plunger and selective key operated connections for causing said plunger to avoid 20 the ejector.

25 3. In a change making device, a money changing unit including a plurality of coin holders, ejectors for the holders, a plurality of 30 sliding plungers adapted to operate said ejectors, a single key for actuating all of the said plungers in unison, and a plurality of selective keys having individual connections with a portion of each plunger to cause the 35 same to avoid or engage the ejector therefor as desired.

40 4. In a change making device, a money changing unit including a coin holder, an ejector therefor, a sliding plunger for operating the ejector, a key for actuating the plunger, means associated with the plunger for directly engaging with the ejector and selective key operated connections for controlling the position of said means thereby 45 to permit the same to engage or avoid the ejector as desired.

45 5. In a change making device, a money changing unit including a coin holder, an ejector therefor, a sliding plunger, a shiftable 50 ejector engaging member connected with the plunger, a key for actuating said plunger, and selective key operated connections for shifting the position of said ejector engaging member independently of the movement of the plunger.

55 6. In a change making device, a money changing unit including a coin holder, an ejector therefor, a sliding plunger, an ejector engaging member pivotally connected with 60 said plunger, and selective means for controlling said ejector member whereby it may engage or avoid the ejector as desired.

65 7. In a change making device, a money changing unit including a coin holder, a coin 65 ejector therefor, and means for selectively

operating said ejector including a sliding plunger, an ejector engaging member pivotally connected to said plunger, key operated connections for actuating said plunger, selective key operated connections for shifting 70 the ejector engaging member from its normal position to an inoperative position, said means including levers connected with the ejector member, a key for operating said levers and a detent device for engaging with 75 said key to hold the same depressed until the operative stroke of the sliding plunger is completed.

8. In a change making device, a money changing unit including a coin holder, a coin 80 ejector therefor, a shiftable plunger, an ejector engaging member pivotally carried by the plunger, a key for actuating the plunger, a spring for normally maintaining the ejector member in position to engage with the 85 ejector, and key operating connections for shifting said ejector engaging member against the tension of its holding spring to shift the same to an operative position with 90 respect to the ejector.

9. In a change making device, a money changing unit including a coin holder, an ejector therefor, a shiftable plunger device for said ejector consisting of a casing having the front end thereof cut away and also 95 provided with guide slots, a plunger shiftable in said casing and having abutments engaging in said guide slots, an ejector engaging hammer pivotally connected with the end of the plunger and disposed in the 100 said cut away portion of the casing, a spring for holding said ejector engaging member in axial alinement with said plunger, key operated connections for engaging one of the 105 abutments on the plunger to actuate the same, and key operated connections for engaging with the relatively free end of the hammer to shift the same out of alinement with the axis of the plunger and in position 110 to avoid the ejector.

10. In a change making device, a money changing unit including a coin holder, a coin 115 ejector for the holder, a shiftable plunger device for operating said coin ejector and consisting of a plunger having offset abutments, guide means for said abutments, an ejector engaging hammer pivotally connected with the plunger, key actuated instrumentalities connected with said hammer to shift the same into and out of position 120 to engage with the coin ejector, detent means for holding the said key operated instrumentalities in position to maintain the hammer inoperative with respect to the coin ejector, key operated connections for engaging with one of the abutments on the plunger device for actuating the same, and the other of said abutments on said plunger 125 being adapted to actuate the detent means to release the same from holding engage- 130

ment with said key operated instrumentalities.

11. In a change making device a money changing unit including a coin holder, and a coin ejector therefor, a plunger device for actuating said coin ejector and including a slideable bar, spaced abutments carried thereby, an ejector engaging hammer pivotally connected with the bar and normally in axial alinement therewith thereby to engage with the coin ejector upon the forward stroke of the bar, key operated means for engaging with one of the abutments on the bar for actuating the same, selective key operated means connected with the hammer to shift the same out of position to avoid the coin ejector, and restraining means for holding the selective key depressed, said restraining means adapted to be engaged by one of said abutments on the bar near the end of its forward stroke to release the selective key operating means.
12. In a change making device, a money changing unit including a coin holder, a coin ejector therefor, a plunger device including a pivoted ejector engaging hammer for actuating said coin ejector, key operated connections for engaging with the plunger device to actuate the same, and a selective key unit for rendering the hammer inoperative, said selective key unit including a key having a stem provided with a portion of substantially U-shaped formation, a spring for yieldingly supporting said key in its normally elevated position, a lever adapted to be engaged by said key, a link connecting said lever with the hammer of the plunger device, and a detent for engaging with the end of the substantially U-shaped portion of the key stem to hold the key in a depressed position, and an abutment carried by the plunger device and adapted to engage the detent to release the

same from holding engagement with the stem.

13. In a change making device, a money changing unit including a plurality of coin holders, a coin ejector for each holder, a plunger device for each ejector, a single amount tendered key for the unit, a lever member operated by said amount tendered key and having a portion common to all of the plunger devices of the unit for actuating the same, an amount purchased key for each individual plunger, connections between said key and the plunger for determining its operative relation with respect to its corresponding coin ejector, and other amount purchased keys adapted to engage with one or more of said connections independently of the first mentioned amount purchased keys to thereby render one or more of said plungers inoperative.

14. In a change making device, a plurality of money changing units, a plurality of coin holders for each unit, ejectors for the coin holder, slideable plungers for operating said ejectors, an amount purchased key for actuating the plungers of each unit, amount purchased keys in each unit operatively connected with the plungers to control their operative relation with respect to their corresponding coin ejectors, detent means for maintaining said amount purchased keys in their downward position when depressed, a releasing bar common to all of the detents of all the units, and a single release key for actuating said release bar.

In testimony whereof I hereunto affix my signature in the presence of two witnesses.

ANGELO PAPOULIAS.

Witnesses:

HARRY L. MAY,
ALMA PHILLIPS.
